SMOKING PIPE

Henry Allen Browne, 4141 King Drive,
Chicago, Ill. 60653

Filed June 9, 1972, Ser. No. 263,743

Term of patent 7 years

Int. Cl. D27—02

U.S. Cl. D85—8 A

FIG. 1

FIG. 2

FIG. 3

FIG. 4

FIG. 1 is a top plan view of a pipe showing my new design;

FIG. 2 is a side elevational view thereof;

FIG. 3 is an end elevational view thereof; and

FIG. 4 is a sectional view taken on the line 4—4 of FIG. 1.

I claim:

The ornamental design for a smoking pipe, as shown.
